UNITED STATES PATENT OFFICE.

GWYLLIM S. LODWICK, OF MYSTIC, IOWA.

METHOD OF FORMING WELLS.

1,009,159.

Specification of Letters Patent. Patented Nov. 21, 1911.

Application filed August 14, 1911. Serial No. 643,867.

To all whom it may concern:

Be it known that I, GWYLLIM S. LODWICK, a citizen of the United States, residing at Mystic, in the county of Appanoose and State of Iowa, have invented certain new and useful Improvements in Methods of Forming Wells; and I do declare the following to be a full, clear, and exact description of the invention, such as will enable others skilled in the art to which it appertains to make and use the same.

This invention relates broadly to the art of excavating, and more especially it is a method or system of treating quicksand, sand, gravel and similar granular strata which is naturally more or less moist and which the engineer may find, possibly beneath the surface stratum, at a point where he desires to sink a well or to form the foundation for a bridge, a building, or the like. Heretofore various attempts have been made to solidify such a mass by injecting cement, sulfur and asphaltum, and other substances some of which depended more or less upon the moist or wet condition in which the granular stratum was found, but by experience I have learned that occasionally the engineer will strike dry sand or gravel which can be treated by my improved process, or that where it is attempted to treat moist sand and the like the moisture is sometimes so excessive that the cement injected thereinto never fairly sets and dries.

The present invention will be well understood from the following specification, taken in connection with the attached drawings, wherein—

Figure 1 designates a vertical sectional view through the earth showing a surface stratum of ordinary soil, a substratum of quicksand, sand, gravel, or the like, and beneath that a base as of rock; and designates some of the steps of my improved process as will be explained; Fig. 2 is a diagrammatic view wherein the slotted lines indicate areas which are treated by my improved process as explained below, for the purpose of producing a rectangular foundation or area as indicated by the solid lines; Fig. 3 is a perspective sectional view through the earth and a stratum of granular material, and a section through a foundation formed by my process in said stratum, the earth above the foundation being removed so that the superstructure can be erected thereon; Fig. 4 is a horizontal section through the earth and a

diagrammatic view of a somewhat smaller frame than that illustrated in Fig. 2, surrounding an objective area in which a well is to be drilled.

In the prosecution of engineering enterprises it often occurs that a stratum of quicksand, sand, gravel, or the like, either dry or moist, is encountered below the surface stratum or "top dressing" which is usually of earth as indicated in Fig. 1; and this granular stratum is extremely difficult to treat with a drill, auger, or pump, cannot easily be blasted, and forms an insecure support for piles or the like which may be driven into it. Investigation proves that the stratum is too deep or thick to permit of its being dug out so that the engineer may reach the solid sub-stratum on which to build his foundation or in which to drill his well, and as the location of his enterprise is established and cannot be moved he is confronted with the problem of treating the granular stratum from the surface in such way as to either solidify a sufficient area to permit him to bore through it subsequently or to solidify an annular or rectangular area or "frame" around the spot through which he desires to bore or upon which he desires to superimpose his foundation, which frame will be sufficiently large and heavy to prevent the inflow of further aqueous granular material which would rot the driven wooden piles, render the foundation unstable, or fill the well yet to be formed. My improved manner of meeting and overcoming these conditions is by means of a process which may be said to involve three distinct steps, to wit: the proper selection of treatment points upon the earth to outline and later to build said "frame" around the area constituting the ultimate objective, the proper sinking of the holes through said points and the injection of cement thereinto, and the final proper treatment of what might be called the objective area. These steps of my process will now be described.

First, the letter A in Fig. 2 may designate the objective area which the engineer designs for subsequent treatment. The initial step of my improved process consists in locating this area around the spot where the well is finally to be sunk or upon which the foundation is to rest, and if by preliminary borings he discovers that there is beneath and around this area a stratum of

granular material such as above described, he first drills holes H around this area and some little distance remote from it, and as each hole is drilled he sinks in it and drives

5 through the granular stratum a well casing

C. The order in which said holes are drilled and casings are sunk is—for a rectangular area A as shown—indicated by the numerals

10 to 6 in Fig. 2, although there would be 10 more of such holes around and possibly spaced farther from a larger area, and if a smaller and perhaps square area A were being treated four holes at its corners might answer. The idea is that this preliminary 15 set of holes is to form a skeleton frame in a manner to be described below, and four of them at least should be disposed at the corners of the area A. In ordinary circumstances and with the usual equipment of machinery, these holes are drilled one at a 20 time and as soon as the first is formed the drill is moved to a proper point to form the second, and so on around the frame.

The next step of my improved process 25 consists in treating said holes. As soon as the drill has been moved from hole number 1 to hole number 2, ordinary cement mixed with a large proportion of water is forced 30 down the well casing C by hydraulic pressure, and the casing of hole number 1 pulled up about a foot as indicated at the left of Fig. 1 so that the cement is allowed to flow out laterally into the sand. After a time the latter will become choked or impregnated 35 with the cement and the pressure gage on the pump will register that fact. The shading at P in Fig. 1 shows this condition. The casing is then raised another foot where it is allowed to remain while more aqueous cement 40 is injected, until the sand surrounding the hole farther up is impregnated with cement. This condition is indicated by the letter P' in Fig. 1. This treatment is repeated and continued until the entire stratum of sand 45 has been thoroughly impregnated with cement, when the casing can be removed from the hole as seen at the right of Fig. 1. Meanwhile hole number 2 will have been drilled, and the machine moved to hole number 50 3; and as soon as hole number 1 has been treated as just above described the treatment is carried to hole number 2, and so on around the frame. It is to be understood that the aqueous cement is injected under hydraulic 55 pressure which is of such force and duration proportionate to the nature of the granular stratum being treated, that when the casing is drawn up a step as indicated, the liquid cement is driven laterally into the stratum 60 for some considerable distance; and, assuming that the nature of the granular material is the same on all sides of each hole, the dotted circles (see letter I, Fig. 2) may represent the extent of the impregnated area 65 around each hole H, and hence it will be

observed that the holes were originally sunken at such distances apart that these impregnated areas would not overlap each other. The preliminary "frame" may therefore be said to have interstices indicated by the reference letter i in Fig. 2 after this first series of six holes has been treated.

The next step of my improved process is but a continuation of the first part of it 75 excepting that the holes H' are bored or sunken between and preferably a little inside of the original series of holes H or opposite said interstices i; and when these holes are treated with the aqueous cement under hydraulic pressure their areas I' would naturally overlap the areas I of the original set of holes as indicated at i' in Fig. 2. It is quite possible that the operator may find 80 reasons to vary the location of this second set of holes, which I have numbered from 8 to 12 in Fig. 2, because he may run onto some of the impregnated granular material from the first set of holes. Ordinarily it 85 would appear that if the second set of holes are disposed midway between those in the first set and the same mixture of cement and water and the same hydraulic pressure is used throughout the process, the engineer might locate the second set of holes with 90 precision; but it must be remembered that the sub-soil conditions vary at different points and perhaps his hydraulic pressure for hole number 1 did not impregnate an area as large as that indicated by the circle 95 100 I or, if the gravel were larger there and the interstices between the individual pieces were larger, the aqueous cement impregnated a much larger area than thus indicated. This he will readily discover when he sinks 105 his second set of holes, for it is obvious that he cannot twice impregnate the same point; and in any event the pressure gage on the injector will indicate when a serious obstruction has been met, and the experienced operator can well judge conditions therefrom. It may therefore be said broadly speaking 110 that the second set of holes are disposed in the spaces or interstices between the impregnated areas around the first set, leaving 115 the engineer some latitude as to how far between and at what intervals all holes are spaced. By preference the holes are drilled and the casing inserted and drawn upward and the aqueous cement injected in this second set of holes, in the same manner as was 120 described with respect to the first set.

The next step in my improved process consists in a repetition of the step just described, excepting that the holes H'' are 125 here sunken within the objective area A which is to receive the final treatment, and if said area is rectangular as shown in Fig. 2 there will be two of such holes H'' side by side, or properly disposed for a larger area, 130

as will be understood. These holes are formed and treated in the manner above described, excepting that possibly the hydraulic pressure may be increased for purposes which will appear. The treatment of the first six holes clearly left interstices between the impregnated areas I, and these interstices were supposed to have been filled by the treatment of the second set of six holes disposed between those in the first set so as to close said interstices; but the chances are that the treatment of all twelve holes in said frame will not have formed a perfectly water-tight mass of concrete around the objective area, and therefore the obvious purpose of the last two holes H" and the injection of aqueous cement into them is both to form impregnated areas I" and to fill up the gaps in the frame. The treatment of the last two holes 13 and 14 in the manner above described therefore impregnates the areas I", or such portions thereof as have not already been impregnated, as shown where these areas overlap at i", for of course the cement injected in the holes H" cannot flow laterally into the sand already once impregnated. The result will be that it will be forced into any leaks that exist within the surrounding body or frame of concrete and may therefore be said to form a solid "core" within said frame, especially if the hydraulic pressure be increased a little. This ends the process of the superstructure 25 is merely to be superimposed upon this foundation, although such is rarely the case. If holes are to be drilled into the objective area A and the superstructure attached to the foundation, they can be formed in the ordinary manner as the aqueous cement will mix with the granular stratum to which it is injected and soon set into a solid mass of concrete which will of course be beneath the earth or top-dressing, as indicated at the right of Fig. 1, and therefore at a proper point to form the foundation for a superstructure. Care must be taken to have the viscous or pasty injection contain a proper proportion of cement and water, due respect being had to the nature of the granular stratum to be impregnated and therefore to be mixed with this injection by reason of the hydraulic force and eventually to form the components of the concrete when the impregnated area has set. By this I mean that if the granular stratum be entirely dry, much water must be mixed with the cement as will be obvious; but on the other hand if the stratum be wet such as quicksand, and experiment shows that the moisture cannot be exhausted by suction up the drilled hole, a smaller proportion of water will be admixed with the cement in the first place and the deficiency will be supplied by the water in the granular stratum. The engineer will also take into consideration the character of the material composing said stratum, and it may be necessary to vary the solid constituents of the injection accordingly. However, these details may well be left to the operator as they form no part of the present invention.

The final step of my improved process, if the objective is a well rather than a foundation, consists merely in drilling the well through the objective area A as through stone, or sinking any kind of a shaft through this area, after a proper length of time has elapsed in which to allow the cement to set; but in this last step care should be taken not to use excessive charges of dynamite or other explosives. The prosecution of this step is too well known to need explanation or illustration, but it will be clear that if the area to be thus bored, drilled, or treated, is surrounded by a frame composed of a preliminary and separated set of areas I (now set into solid masses) and a second and intermediate set of areas I" (now also set) interposed between the areas of the first set, and the objective area A itself is larger than the hole, shaft, or mine to be sunk so that its plastic (now also set) has filled all holes in the frame, the formation of the final hole through the center of this objective area can be prosecuted without fear of the walls thereof caving in or leaking. It is to be assumed, of course, that this process has been carried out for the full depth of the stratum of sand or other granular material, and the experienced engineer will know how to treat the walls of said hole above and below this troublesome stratum. The latter may be located near the earth's surface as shown in Fig. 1, or far beneath; and in fact in the sinking of a deep shaft the engineer may pass through a plurality of granular strata, each of which may be treated successfully and successively by the method herein described.

I have purposely amplified the steps of this improved method beyond what is perhaps ordinarily necessary in a patent specification for reasons which I will explain, but desire not to be limited too strictly to the details thereof as the gist of my idea is set forth in the appended claims. Efforts have hitherto been made to treat quicksands and other granular strata by methods more or less similar to the one herein described, but in my experience I have not met with one which involved the steps above set forth. Injection of liquid or pasty cement into a granular substance is well known, as also the formation of a dam around an area which is to be the object of subsequent treatment; but I have gone into detail in the above specification to show how a frame could be formed in a

granular stratum by the method whose broad principles are well known, with the result that an objective area is produced within said frame which is capable of final treatment for the purposes desired. Moreover, at the present time the business of sinking shafts and mixing and forming concrete is often practiced by persons who are not as experienced as engineers in these lines should be, and I have therefore amplified details throughout this specification in order to appeal to and be understood by a person of average intelligence and experience along these lines.

18 In Figs. 3 and 4 of the drawings are shown amplifications of my idea. The former illustrates in full lines how a foundation could be built by this improved process, having a considerable objective area indicated by the letter A as made up of two internal impregnated fields or areas I'' surrounded by a frame made up of two series I and I' of impregnated fields or areas arranged in staggered relation to each other. 25 Fig. 4 is a diagrammatic plan view much like that of Fig. 2 excepting that the outside and inside series have four fields or areas each, and the objective area may be formed by drilling a single hole and impregnating the granular material with aqueous cement under a higher degree of pressure. In Fig. 3 the dotted lines K show how the foundation could be cut through to form a rectangular mine shaft downward through such a protecting frame and through the center of the objective area, and in Fig. 4 the dotted circle W within the objective area indicates how a round well might be drilled.

40 What is claimed as new is:

1. The herein described method of treating an objective area in a granular stratum, the same consisting in first sinking a series of holes around said area and at some distance apart, then inserting a well casing in each hole to a point near the bottom of said stratum, then injecting aqueous cement under pressure sufficient to impregnate the granular material around said hole, then lifting the casing for a distance and repeating the injection and impregnation, and continuing this process until the stratum is impregnated for areas around all said holes; and second sinking and similarly treating a second series of holes disposed between those in the first series and at such distance therefrom that the impregnated areas of the second series will reach those of the first.

2. The herein described method of treating an objective area in a granular stratum, the same consisting in first sinking a series of holes around said area and at some distance apart, then inserting a well casing in each hole to a point near the bottom of said stratum, then injecting aqueous cement

under pressure sufficient to impregnate the granular material around said hole, then lifting the casing for a distance and repeating the injection and impregnation, and continuing this process until the stratum is impregnated for areas around all said holes; second sinking and similarly treating a second series of holes disposed between those in the first series and at such distance therefrom that the impregnated areas of the second series will reach those of the first; and finally sinking and similarly treating holes within said objective area and of such numbers and disposition that their impregnated areas will complement and fill interstices in the areas that have been previously impregnated.

3. The herein described method of forming wells and the like through an objective area in a granular stratum, the same consisting in first sinking a series of spaced holes around said area, inserting a well casing in each hole to a point near the bottom of said stratum, injecting aqueous cement under pressure sufficient to impregnate the granular material around said hole, lifting the casing for a distance and repeating the injection and impregnation, and continuing this process for all the holes of the series until the full depth of the stratum is impregnated around them; second sinking and similarly treating a second series of holes disposed between those in the first series and at such distance therefrom that the impregnated areas of the second series will reach those of the first; third sinking and similarly treating holes within the objective area and of such numbers and disposition that their impregnated areas will reach each other and those of said series and complement and fill the interstices in the latter; and finally forming the well through said objective area after all cement has set.

4. The herein described method of protecting an objective area in a stratum of granular material, the same consisting in first sinking a series of holes in said stratum around and slightly remote from said area and impregnating the granular material around the holes by injecting aqueous cement under pressure, and then sinking a second series of holes therein around and nearer to said area and between the other holes and similarly treating said holes of the second series.

5. The herein described method of protecting an objective area in a stratum of granular material, the same consisting in forming a frame around the area by sinking in said material a double series of holes in staggered relation to each other, and impregnating the material around each hole with aqueous cement under hydraulic pressure, treating first those holes in one series and then those in the other and employing

- sufficient pressure to cause the cement injected in the last series to impregnate the material around each hole radially outward to the areas already impregnated around the contiguous holes of the first series.
6. The herein described method of producing an objective area in a stratum of granular material, the same consisting in first forming a frame around said area by sinking a number of holes through said material and injecting into them aqueous cement under hydraulic pressure sufficient to impregnate the material around each hole radially outward to the impregnated areas around the adjacent holes, and then sinking holes in said objective area and treating them in the same manner but subjecting them to a higher pressure.
7. The herein described method of forming a well or the like through a stratum of granular material, the same consisting in first defining an objective area; second forming a frame around said area by sinking a number of holes through said material and injecting into them aqueous cement under pressure sufficient to impregnate the material around each hole radially outward to the impregnated areas around the adjacent holes; third repeating the process within said objective area but employing a higher degree of pressure; and finally forming the well through said objective area after the cement within it has set.
8. The herein described method of producing an objective area in a stratum of granular material, the same consisting in first forming a frame around the area by sinking in said material a double series of holes in staggered relation to each other, and impregnating the material around each hole with aqueous cement under pressure to cause the cement injected in the last series to impregnate the material around each hole radially outward to the areas already impregnated around the contiguous holes of the first series; and then sinking a number of holes in said objective area and treating them in the same manner but subjecting the injection therein to a higher pressure.
- In testimony whereof I have hereunto set my hand in presence of two subscribing witnesses.
